METHOD OF SOLUBILIZING STEROIDS

Wilbert J. Humphlett and Charles V. Wilson, Rochester, N. Y., assignors to Eastman Kodak Company, Rochester, N. Y., a corporation of New Jersey

No Drawing. Application August 9, 1956
Serial No. 603,194

14 Claims. (Cl. 260—397.2)

This invention relates to new compositions of matter, more particularly to water-soluble steroids, and their preparation.

The term steroid is used to include sterols, bile acids, sex hormones, and the like.

The sterols are a group of complex alicyclic alcohols. They are colorless, crystalline solids, soluble in organic solvents, and usually found in the unsaponifiable portion of fats. Many of these compounds have great use for medicinal purposes, but their solubility in organic solvents has limited their usefulness, and, therefore, it has been desired to find some way of increasing the solubility in water of these materials. Methods which have been suggested include solubilizing with materials which are not acceptable to the human system. Consequently, the problem of finding a solubilizing means for these very complex molecules for medicinal purposes has been complicated by the requirement that the solubilizing method provide compounds which would be acceptable to the human system.

Typical bile acids, isolated by the saponification and processing of biles of various animals, are C_{24} -substances having one carboxyl group and one, two, or three secondary alcoholic groups.

We have found that steroids can be solubilized according to our process into materials which are not only water-soluble but also can be taken into the human system without damaging the system due to the solubilizing groups.

One object of this invention is to provide water-soluble steroids. Another object of this invention is to provide a method for solubilizing complex molecules such as those found in steroids and the like. An additional object is to provide a solubilizing compound which provides an amino acid on normal hydrolytic cleavage which has no detrimental effect upon the human system.

We have found that these complex molecules can be solubilized by treating the materials with a requisite amount of an isocyanato ester, and selectively hydrolyzing the ester group. The hydrolysis may be effected by use of the hydroxides or carbonates of sodium, potassium, or lithium or by other basic substances such as alkyl primary, secondary, or tertiary amines. In our preferred embodiment, the isocyanato ester is derived from glutamic or aspartic acid, but other isocyanato esters may be used such as those derived from the simpler amino acids such as glycine, alpha-alanine, leucine, and the like.

Isocyanato esters of the structure $OCN(CH_2)_nCOOR'$ or $CH_3(CH_2)_mCHNCO(CH_2)_nCOR''$ may also be employed, in which n and m may be whole numbers from 1-3. Isocyanato esters such as those derived from para-aminophenylacetic or para-aminophenylsuccinic acid also fall within the scope of the invention.

The following general equations illustrate the type of reaction involved:

2

R represents the steroid radical or the steroid molecule less the hydroxyl group in the first equation, the steroid molecule less the carboxyl group in the second. R' may be H, alkyl such as CH_3 , C_2H_5 and $(CH_3)_2CH$ or aryl such as C_6H_5 , or CH_2COOR'' , CH_2CH_2COOR'' . R'' may be CH_3 , C_2H_5 or some other lower alkyl.

The following examples are intended to be illustrative of our invention but are not intended to limit it in any way:

10 *Example 1.—Reaction of mixed soybean sterols with dimethyl α -isocyanato glutarate*

A solution of 5 g. (0.011 mole) of mixed soybean sterols (consisting of 24.4% stigmasterol, 69.6% β - and α -sitosterol and campesterol and 6% of long chain hydrocarbons), 2 g. (0.01 mole) of dimethyl α -isocyanato-glutarate and 25 ml. of xylene was refluxed 5 hours and the solvent removed under reduced pressure. The solid ester, which amounted to 7 g. was recrystallized from 200 ml. of methanol yielding 5.2 g., M. P. 115-117°. Saponification of the ester in 95% ethanol with potassium hydroxide yielded a white, free-flowing powder which was readily water-soluble.

To demonstrate the solubility of this product, 0.4 g. was dissolved in 2.5 ml. of water. The soybean sterols are insoluble in water.

25 *Example 2.—Reaction of β -sitosterol with dimethyl α -isocyanato glutarate*

30 A soybean sterol, β -sitosterol, was reacted with dimethyl α -isocyanato glutarate to yield the disodium salt of a water-soluble urethane as follows:

A solution of 1.5 g. (0.0036 mole) of β -sitosterol (M. P. 134-136°), 0.66 g. (0.0033 mole) of dimethyl α -isocyanato-glutarate and 25 ml. of xylene was treated in a manner identical to that in the foregoing example and saponified with 0.5 g. of potassium hydroxide in 100 ml. of 95% alcohol. The product, a white, free-flowing powder, amounted to 1.8 g. (80%).

For purification the potassium salt was dissolved in water and acidified with hydrochloric acid giving a precipitate of the corresponding acid derivative. This derivative was collected, dried, and dissolved in ethyl alcohol. To this solution was added an alcohol solution containing a 5% excess of potassium hydroxide. The precipitated salt obtained melted at 286° and is readily soluble in water, e. g.—1.6 g. dissolved easily in 6 ml. of water. β -Sitosterol, itself is insoluble in water.

The acid derivative, recrystallized twice from ethyl ether, melted at 193°.

Analysis.—Calc'd for $C_{35}H_{57}O_6N$: C, 71.5; H, 9.8; N, 2.4. Found: C, 71.7; H, 9.4; N, 2.7.

Example 3.—Reaction of campesterol with dimethyl α -isocyanatoglutarate

A solution of 2 g. (0.005 mole) of campesterol (M. P. 153–156°), 0.91 g. (0.0045 mole) of dimethyl α -isocyanatoglutarate and 25 ml. of xylene was treated in a manner identical to that in the foregoing example and saponified with 0.6 g. of potassium hydroxide in 100 ml. of 95% alcohol. The salt obtained amounted to 2.8 g., M. P. 281°.

To demonstrate the solubility of the product, a sample of 0.5 g. was readily dissolved in 1.5 ml. of water. Campesterol, itself, is insoluble in water.

The acid derivative was prepared and recrystallized twice from ethyl ether, M. P. 197–198°.

Analysis.—Calc'd. for $C_{34}H_{55}O_6N$: C, 71.2; H, 9.6; N, 2.4. Found: C, 71.3; H, 9.3; N, 2.8.

Example 4.—Reaction of stigmasterol with dimethyl α -isocyanatoglutarate

A solution of 15 g. (0.036 mole) of stigmasterol (M. P. 167–169°), 6.6 g. (0.033 mole) of dimethyl α -isocyanatoglutarate and 100 ml. of xylene was treated in a manner identical to that in the foregoing example and saponified with 5 g. of potassium hydroxide in 200 ml. of 95% alcohol. The product amounted to 23 g. For purification the potassium salt was dissolved in water, acidified, and the acid derivative which separated was extracted with ether. The combined ether phases were re-dried over anhydrous sodium sulfate and the solvent removed. The acid derivative obtained in this manner was dissolved in alcohol and added to a 5% excess of potassium hydroxide dissolved in alcohol. The precipitated potassium salt which was collected melts at 282°.

In order to demonstrate the solubility of this product, a 1 g. sample was readily dissolved in 3 ml. of water. Stigmasterol, itself, is insoluble in water.

The following is the structural formula of the product:

The acid derivative was recrystallized twice from ethyl ether, M. P. 203°.

Analysis.—Calc'd. for $C_{35}H_{55}O_6N$: C, 71.8; H, 9.5; N, 2.4. Found: C, 71.9; H, 9.9; N, 2.5.

Example 5.—Reaction of stigmasterol with methyl 6-isocyanatohexanoate

A solution of 1.52 g. (0.0037 mole) of stigmasterol, 0.63 g. (0.0037 mole) of methyl 6-isocyanatohexanoate (B. P. 68° at 1 mm., n_D^{26} 1.4448) and 100 ml. of xylene was treated as in the foregoing example yielding the corresponding ester which, recrystallized from alcohol, amounted to 1.8 g. (89%), M. P. 99°.

Analysis.—Calc'd. for $C_{37}H_{61}O_4N$: C, 76.1; H, 10.5; N, 2.4. Found: C, 76.4; H, 10.8; N, 2.1.

This potassium salt can be used to prepare dilute aqueous solutions. Stigmasterol, itself, is insoluble in water.

Example 6.—Reaction of testosterone with dimethyl α -isocyanatoglutarate

A mixture of 5 g. (0.017 mole) of testosterone (M. P.

153°, E (1%, 1 cm.) (239 m.) = 567), 4 g. (0.02 mole) of dimethyl α -isocyanatoglutarate, 20 ml. of benzene and 5 ml. of pyridine was refluxed for 20 hours. The solvent was removed from the reaction solution under reduced pressure leaving the corresponding urethane-ester as an oil. The ester was saponified with a solution of 2.8 g. of potassium hydroxide in 95% ethyl alcohol by refluxing for 30 min. The potassium salt obtained in this manner was recrystallized from ethyl alcohol yielding 8.7 g. of a pale yellow, solid salt which is readily soluble in water.

Example 7.—Reaction of cholesterol with dimethyl α -isocyanatoglutarate

Cholesterol was reacted with dimethyl α -isocyanatoglutarate to yield the disodium salt of a water-soluble urethane as follows:

A solution of 39 g. (0.1 mole) of cholesterol and 21 g. (0.1+ mole) of dimethyl isocyanatoglutarate in 100 ml. of chlorobenzene was heated under reflux at 120–130° for 3 hours. The chlorobenzene was removed under reduced pressure and the residual urethane-ester dissolved in about 700 ml. of alcohol. The ester crystallized therefrom on cooling. The yield was about 49 g. (82 percent).

The ester was dissolved in one liter of ethanol and treated with 7 g. (5 percent excess) of sodium hydroxide dissolved in 20 ml. of water. The mixture was heated on the steam bath for an hour, chilled, and the product collected and dried. Yield, 47 g. The product has better solubility in water than cholesterol itself. The potassium salt has even greater solubility.

Example 8.—Reaction of cholic acid with ethyl α -isocyanatoacetate

A solution of 41 g. (0.1 m.) of cholic acid and 53 g. (0.41 m.) of ethyl isocyanatoacetate in 100 ml. of chlorobenzene was heated for 2 hours at the boiling point. The solvent was then removed under reduced pressure and the resulting syrup dissolved in about 300 ml. of alcohol. To this solution was added 16 g. of sodium hydroxide (0.4 m.) dissolved in 20 ml. of water and diluted with 200 ml. of alcohol. The sodium salt separated as a "taffy." The mixture was warmed on the steam bath for one-half hour and then chilled. The aqueous alcohol was decanted from the pasty mass, acetone added, and the solid broken up—first by hand, and finally by stirring vigorously with a Lightnin' mixer. The acetone was removed by filtration or decantation, fresh acetone added, and the stirring continued. The granular product (85–90 g.) was finally collected on a filter and dried in a vacu-

um oven. The product had excellent surface-active properties.

The free acid was precipitated from a solution of the sodium salt. The analytical results on this acid indicate that the substance has the following structure:

Analysis.—Calcd. for $C_{32}H_{49}O_{12}N_3$: C, 57.5; H, 7.3; N, 6.3; O, 28.8. Found: C, 57.7; H, 7.0; N, 6.0; O, 29.3. But this has not been definitely established.

The sterols are illustrated by many materials which have been found essential to the proper functioning of the human system. For example, the sex hormones are steroids and have been found necessary for the general importance to the health and well being of humans. In some situations it has been found necessary to add these materials and, therefore, the ability to make them water-soluble will further promote their use and therapeutic benefit. Insufficient production by the human system of these hormones or of other steroids or sterols which are necessary to the human welfare, require that these be added, and, therefore, it is necessary that some means be available for supplying them to the human system which is not only acceptable to the human physiology, but which will enable these materials to perform their intended function.

Our invention provides a new means for making these steroids water-soluble and also providing a solubilizing material which itself is acceptable to the human system, inasmuch as the breakdown of these esters results in the formation of amino acids which are beneficial to the human system and which are non-toxic. Accordingly, the compounds produced according to our invention will be of great utility for therapeutic purposes as well as enabling considerably more research to be carried out in using these materials.

Other compounds which may be solubilized by this procedure are the sex hormones such as estradiol, estrone, estriol, equilenin, diethylstilbesterol, testosterone, androsterone, pregnanediol, and related compounds, and the cortical steroids such as cortisone, desoxycorticosterone, 11-dehydrocorticosterone, 17-hydroxydesoxycorticosterone, 17-hydroxycorticosterone, 17-hydroxy-11-dehydrocorticosterone, and their derivatives.

We claim:

1. A process of solubilizing stigmasterol comprising reacting it with an isocyanato ester having the following formula

in which R is an alkyl group having 1-4 carbon atoms, n is an integer from 1 to 6 and R' is selected from the class consisting of hydrogen, alkyl having 1-3 carbon atoms and COOR, and selectively hydrolyzing the said ester linkage with alkali.

2. A composition of matter obtained by the process described in claim 1.

3. A process of solubilizing sitosterol comprising reacting it with an isocyanato ester having the following formula

in which R is an alkyl group having 1-4 carbon atoms, n is an integer from 1 to 6 and R' is selected from the class consisting of hydrogen, alkyl having 1-3 carbon atoms and COOR, and selectively hydrolyzing the said ester linkage with alkali.

4. A composition of matter obtained by the process described in claim 3.

5. A process of solubilizing campesterol comprising reacting it with an isocyanato ester having the following formula

in which R is an alkyl group having 1-4 carbon atoms, n is an integer from 1 to 6 and R' is selected from the class consisting of hydrogen, alkyl having 1-3 carbon atoms and COOR, and selectively hydrolyzing the said ester linkage with alkali.

6. A composition of matter obtained by the process described in claim 5.

7. A process of solubilizing cholesterol comprising reacting it with an isocyanato ester having the following formula

in which R is an alkyl group having 1-4 carbon atoms, n is an integer from 1 to 6 and R' is selected from the class consisting of hydrogen, alkyl having 1-3 carbon atoms and COOR, and selectively hydrolyzing the said ester linkage with alkali.

8. A composition of matter obtained by the process described in claim 7.

9. A process of solubilizing testosterone comprising reacting it with an isocyanato ester having the following formula

in which R is an alkyl group having 1-4 carbon atoms, n is an integer from 1 to 6 and R' is selected from the class consisting of hydrogen, alkyl having 1-3 carbon atoms and COOR, and selectively hydrolyzing the said ester linkage with alkali.

10. A composition of matter obtained by the process described in claim 9.

11. A process of solubilizing sterols comprising reacting a sterol with an isocyanato ester having the following formula

in which R is an alkyl group having 1-4 carbon atoms, n is an integer from 1 to 6 and R' is selected from the class consisting of hydrogen, alkyl having 1-3 carbon atoms and COOR, and selectively hydrolyzing the said ester linkage with alkali.

12. A composition of matter obtained by the process described in claim 11.

13. A process of solubilizing steroids selected from the class consisting of stigmasterol, sitosterol, campesterol, cholesterol, testosterone, cholic acid, estradiol, estrone, estriol, equilenin, diethylstilbesterol, androsterone, pregnanediol, cortisone, desoxycorticosterone, 11-dehydrocorticosterone, 17-hydroxydesoxycorticosterone, 17-hydroxycorticosterone, and 17-hydroxy-11-dehydro-

7 corticosterone by reacting the steroid with an isocyanato ester having the following general formula

in which R is an alkyl group having 1-4 carbon atoms, n is an integer from 1 to 6 and R' is selected from the class consisting of hydrogen, alkyl having 1 to 3 carbon atoms and COOR and selectively hydrolyzing the said ester linkage with alkali. 10

14. A composition of matter obtained by the process described in claim 13.
